DESIGN FOR A BURIAL BASE

Richard S. Donahey, Columbus, Ohio

Application April 24, 1936, Serial No. 62,289

Term of patent 14 years

To all whom it may concern:

Be it known that I, Richard S. Donahey, a citizen of the United States, residing at Columbus, in the county of Franklin and State of Ohio, have invented a new, original, and ornamental Design for Burial Bases, of which the following is a specification, reference being had to the accompanying drawing, forming part thereof.

I claim:

The ornamental design for a burial base, as shown.

RICHARD S. DONAHEY.
